UNITED STATES PATENT OFFICE.

EDGAR FULLER, OF FORT ASSINNIBOINE, MONTANA.

SASH-FASTENER.

SPECIFICATION forming part of Letters Patent No. 624,783, dated May 9, 1899.

Application filed August 15, 1898. Serial No. 688,596. (No model.)

To all whom it may concern:

Be it known that I, EDGAR FULLER, a citizen of the United States, residing at Fort Assiniboine, in the county of Chouteau and State 5 of Montana, have invented certain new and useful Improvements in Sash-Fasteners; and I do hereby declare the following to be a full, clear, and exact description of the invention, such as will enable others skilled in the art to 10 which it appertains to make and use the same.

This invention relates to improvements in sash-fasteners of that class embodying a gear and rack and means for holding the gear stationary to support the sash at any desired 15 distance from the top or bottom of the window-frame; and the object of the invention is to provide a simple and effective fastener of this character having improved means for automatically locking the gear against rotation. 20

To this end the invention consists in certain novel features of construction, combination, and arrangement of parts, as will be hereinafter more fully described, and particularly pointed out in the appended claim. 25

In the accompanying drawings, Figure 1 is a fragmentary elevation of a window frame and sash with parts broken away to show the invention applied thereto. Fig. 2 is a vertical longitudinal section through the gear-case on an enlarged scale. Fig. 3 is a vertical transverse section of the same. Fig. 4 is a detail view of the spring-clamps and coacting block on the pinion. Fig. 5 is a similar view 35 of the pinion. Fig. 6 is a front view of the slotted rack-plate.

Referring now more particularly to the drawings, wherein like letters of reference designate corresponding parts throughout the 40 several views, A represents a window-frame, and B a window-sash mounted to slide vertically therein in the usual manner.

To the inner face of the side of the casing is secured a plate C, slotted at regular intervals to form a series of rack-teeth d, said plate being preferably seated in a recess, so that the outer surface thereof will be flush with the casing. The contiguous stile of the window-sash is mortised to receive a casing E, the 45 front wall of which is provided with ears for passage of screws to secure it to the stile and with a slot F. Arranged in the case is a spur-

pinion G, which projects through the slot and meshes with the said rack-plate C, whereby the pinion is caused to revolve as the sash is 55 raised and lowered. This pinion is mounted on a short shaft or spindle h, journaled in the case and provided with a fixed rectangular block or locking-head i, located on one side of the pinion. 60

Suitably secured at the top and bottom in the case on the same side of the pinion as the locking-head is a pair of spring-metal plates or strips J, each provided centrally with a V-shaped outwardly bent or deflected portion 65 k. The plates are arranged parallel, with their broad sides facing each other, and the said deflected portions thereof are reversely projected and oppositely disposed, thus forming a rectangular keeper-socket for the reception 70 of the locking-head i, which is adapted to be embraced thereby at each quarter-revolution of the pinion to hold the latter firmly against rotation, so that the sash will be supported. By the peculiar construction and arrangement of parts just described it will be seen 75 that when the corners of the locking-head bear against the sides of the V-shaped deflected portions of the spring-plates, as shown in Fig. 4, the latter will spring apart and allow 80 the pinion to turn; but when the broad sides of the head come in contact therewith, as shown in Fig. 2, the plates will close together and embrace the locking-head firmly, so as to hold the same and the pinion against accidental rotation. As the teeth of the pinion 85 are in mesh with the rack, the window-sash will then be supported. The spring-plates are made stiff enough to resist the turning of the locking-head under the tendency of the 90 sash to drop by gravity, and yet sufficiently resilient to allow the spring-keeper to expand and contract and said block to rotate therein freely when the sash is forcibly elevated or depressed. Thus the sash may be 95 conveniently raised and lowered without hindrance and automatically locked at any desired elevation.

It will of course be understood that the arrangement of parts shown and described for 100 purposes of illustration herein may be reversed—that is, the rack-plate placed on the stile of the sash and the casing, with the pinion and its coacting locking mechanism, on

the window-frame—without varying the construction or impairing the efficiency of the device. It will also be understood that changes in the form, proportion, and minor details of construction may be made within the scope of the invention without departing from the spirit or sacrificing any of the advantages thereof.

Having thus described the invention, what is claimed as new is—

In a sash-fastener, the combination of a rack, a casing, a pinion adapted to mesh with the rack and mounted on a shaft or spindle journaled in the casing, an angular locking-head

or block on the spindle at one side of the pinion, and a pair of parallel spring-plates secured at their upper and lower ends in the casing, said plates having their broad sides facing each other and bearing on opposite sides of the locking-head and bent to form an angular keeper-socket normally embracing the same, substantially as described.

In testimony whereof I affix my signature in presence of two witnesses.

EDGAR FULLER.
